UNITED STATES PATENT OFFICE

2,319,178

MILITARY TANK

Frank S. Wrona, Aurora, Ill.

Application September 18, 1940, Serial No. 357,311

1 Claim. (Cl. 98—2)

This invention relates to military tanks, and has for the primary object the provision of a device of this character wherein the body construction thereof will more readily turn or deflect bullets, shrapnel and the like and thereby be less liable to puncture and consequently provide for better protection to the soldiers therein and is also so constructed that it may be thoroughly ventilated to permit smoke and gases to escape and may be easily and quickly closed in case of an encounter with flame throwers or deadly gas devices.

Another object of this invention is to improve the traction thereof on the ground and to afford maximum protection to the soldiers when operating the guns therein.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a top plan view illustrating a military tank constructed in accordance with my invention.

Figure 2 is a side elevation illustrating the device.

Figure 3 is a vertical sectional view illustrating the interior construction of the device.

Figure 4 is a longitudinal sectional view illustrating the interior construction of the device.

Figure 5 is a front elevation illustrating the device.

Figure 6 is a transverse sectional view illustrating the device and especially the ventilating means therefor.

Figure 7 is a fragmentary sectional view illustrating shield plates for affording protection to the gunners while operating machine guns or similar firearms from the device.

Referring in detail to the drawings, the numeral 5 indicates the body of the military tank and 6 the mobile or traction means thereof which is of the caterpillar type, the tread plates being preferably cupped, as shown at 7, to increase their traction upon the ground.

The body 5 is substantially cylindrical shaped having the front end thereof pointed, as shown at 8, while the rear end is rounded, as indicated by the character 9. This shape of the body will more readily deflect bullets, shrapnel or the like striking the same and render the body less liable

to puncture. The walls of the body are constructed of heavy armor plates suitably welded or otherwise secured together. The walls of the body are supported by frame members 10 of I beam construction to provide the necessary strength or rigidity to the body. A subflooring 11 is arranged in the body for the support of firearms therein. The type of firearms employed within the body can be varied. However, it is preferable that guns, as indicated at 12, of an extremely large caliber be mounted in the front end with the barrels thereof protruding through openings 13 provided in the body. The openings 13 also provide vision openings so that the steering or driving of the device can be easily carried out from within.

It may be desirable to arrange the large caliber guns within separate compartments, as shown at 14, with the compartments closed to the main compartment by doors 15.

The smaller caliber guns, such as machine guns, indicated generally by the character 16 are operable from within the body and are fired through openings 17 provided in opposite walls 25 of the body. The openings 17 have slidably mounted therein shield or guard plates 18, the adjacent edges of which are notched to permit the barrels of the guns 16 to protrude therethrough.

Weights 19 are connected to the plates 18 by cables 20 which pass over pulleys for the purpose of maintaining the plates in engagement with each other and which will permit the plates to slide when the gun barrel is swung laterally or horizontally. The notches in the adjacent edges of the plates permit the gun barrels to be moved vertically for a limited distance.

Doorways 21 are provided in opposite sides of the body and are closed by doors 22 arranged to swing outwardly of the body and are secured in closed position by bolts 23 extending through apertured brackets 24 on the doors and having turned thereon nuts 25. The nuts are shaped to provide hand grips so that they can be easily rotated in either direction for securing the doors closed or for freeing the doors.

The body in the upper portion thereof is provided with a series of vent openings 26 which can be opened and closed by shield plates 27 each having secured thereto a depending arm 28. The vent openings 26 are arranged in rows and journaled in the body between the rows of vent openings is an operating shaft 29 to which are secured arms 30 and 31. Links 32 are pivotally connected to the arms 30 and to the depending

arms 28 of one row of the closure elements 27 while the arms 31 have pivoted thereto links 33 which are in turn pivoted to the depending arms 28 of the other row of closure elements. By rotating the shaft 29 in one direction all of the closure elements may be swung into an open position for the purpose of ventilating the interior of the body and to allow smoke, gases and the like to escape from the body. A rotation of the shaft in a reverse direction simultaneously 10 closes all of the closure elements which is desirable in case the device encounters flame throwers and similar war devices.

While I have shown and described the preferred embodiment of my invention, it will be understood that minor changes in construction, combination and arrangement of parts may be made without departing from the spirit and scope of the invention as claimed.

Having thus described my invention, what I claim is:

In an armored tank of the character described, a body having in the top thereof parallel rows of ventilating openings, vertically swingable closure plates for said openings, an operating shaft rotatably mounted in said body intermediate said rows of openings, bearing means for supporting said shaft in said body, arms depending from the closure plates at their hinged edges, arms projecting radially from the shaft in opposite directions, and links pivotally connecting the arms of the plates with the arms of the shaft for simultaneously moving all of said plates to either opened or closed position, optionally.

FRANK S. WRONA.
